(57) CLAIM

The ornamental design for a powder case, as shown and described.

DESCRIPTION

FIG. 1 is a top, front perspective view of a powder case showing my new design;

FIG. 2 is a top plan view thereof;

FIG. 3 is a front elevational view thereof, the rear elevational view being identical; and,

FIG. 4 is a bottom plan view thereof, the broken lines being for environmental purposes only and forming no part of the claimed design.
